Group PC(57) **CLAIM**

What is claimed is the ornamental design for a clip mount for a watch, as shown and described.

DESCRIPTION

FIG. 1 is a top, front, right perspective view of a clip mount for a watch showing our new design;

FIG. 2 is a left side elevational view thereof, the right side being a mirror image of the left side;

FIG. 3 is a front elevational view thereof, the rear being a mirror image of the front;

FIG. 4 is a top plan view thereof;

FIG. 5 is a bottom plan view thereof;

FIG. 6 is a top, front, right perspective view thereof shown with a watch; and,

FIG. 7 is a top, front, right perspective view thereof shown mounting a watch to a steering wheel; wherein the broken lines are for illustrative purposes only and form no part of the claimed design.
